DEVICE FOR CLEANING TANKS AND THE
LIKEHarold M. Ruth, Huntington Park, Calif., assignor
to The Pyrate Corporation of Nevada, a corpo-
ration of NevadaApplication May 26, 1933, Serial No. 672,927
Renewed September 19, 1934

11 Claims. (Cl. 299—67)

This invention has to do in a general way with devices for washing the interior of tanks and the like, and is more particularly related to devices of the general character disclosed in my application, Serial No. 637,028, filed jointly with Clare Richards, on October 10, 1932, in that it is especially adapted for use in cleaning the interior of tank cars.

The general construction of the device contemplated by this invention, like that of the former application referred to above, comprises, what I may term, a main feed conduit adapted to be suspended through the manhole in the dome of a tank by means of a supporting plate.

This main feed conduit is provided at its upper end with means for connection to a suitable source of supply of washing liquid, and at its lower end it is provided with a bearing member which rotatably supports, what I may term, a nozzle unit comprising a secondary feed conduit arranged in coaxial relation with the feed conduit and having on its lower end a hollow nozzle axle or nozzle feed conduit which rotatably supports a nozzle member.

The nozzle member is mounted for rotation in a substantially vertical plane, and means are provided for rotating the secondary conduit or the nozzle unit about the axis of the main feed conduit. Through this construction, it will be seen that the nozzle unit has a rotation first in a vertical plane and second in a horizontal plane, such rotative movements taking place simultaneously so that the interior of the tank is completely covered by the spray or streams from the nozzle member.

In the device of the former application, referred to above, the nozzle member comprises a plurality of individual nozzles mounted on a suitable hub, such nozzles having curved outlet ends so that the force of the jet is effective to rotate the nozzle. Governor means are also provided to control the speed of such rotation.

It is a primary object of this invention to produce a device of the class described with an improved nozzle construction. The nozzle units in this improved nozzle construction are formed with a substantially straight line taper so that there is no check in the flow of fluid therethrough due to a curve or obstruction, and in this way I am able to obtain a stream or jet of much greater force which has much greater cleaning power and which will be carried to the farthest extremities of an ordinary tank car as a substantially solid jet.

In order to rotate a nozzle unit of this character,

I employ a liquid impelled motor which is preferably driven by the pressure liquid that goes to the nozzles. In the development of this device, I have also discovered that it is preferable in effecting a thorough cleaning of a tank to operate the nozzles in a step by step manner. In this way I obtain a direct impingement of the stream against the tank without the sweeping action that attends a continuously moving nozzle, and I am thereby able to effect a more thorough cleaning in less time than is accomplished by the ordinary type of nozzle. It is, therefore, a further object of this invention to provide means operated by the liquid impelled motor to drive the nozzle in the step by step manner referred to, such means in the preferred form of my invention comprising a ratchet mechanism interposed between the nozzle and the motor.

The element of speed is also an important feature in a device of this character, and it becomes another object of this invention to provide means for positively controlling the speed at which the nozzles operate. Inasmuch as the speed of the motor is dependent upon the pressure of the liquid which operates the impeller, I take advantage of this fact to govern the speed by providing a pressure-regulating valve in the passage or passages through which the liquid travels from the feed conduit to the impeller. It is a noteworthy feature of the invention that the valve just referred to may be set so as to operate the nozzle unit at any predetermined speed.

As is well known to those familiar with the art, the length of the tank, or a tank car, is much greater than its diameter so that any angular movement in a stream of liquid coming from a point beneath the dome will produce a much greater linear movement in the stream at the end of the car than at points along the sides of the car. It will be seen, therefore, that in a device wherein the nozzle unit is rotated through a horizontal plane at a uniform angular velocity, the ends of the car will not receive the same cleaning action as is applied to the sides. It, therefore, becomes another object of this invention to provide a device of the class described wherein the angular velocity of the horizontal movement may be varied so that the stream travels slower in traversing the ends of the car than it does when it traverses the sides. In the device contemplated by this invention, like that disclosed in the former application referred to above, the horizontal rotation of the unit is effected by a pawl and ratchet mechanism which is actuated directly from the movement of the nozzle.

The objective, just referred to above, is accomplished by employing a ratchet mechanism which comprises vertically spaced and angularly disposed offset ratchet segments, the upper segments being adapted to engage the upper end portion of the pawl member, and the lower segment being arranged to engage an intermediate point on the pawl member. The lower segment is provided with more teeth per unit of length than the upper segment so that the increments of motion, when the pawl is traversing the lower segment, are less than when the pawl traverses the upper segments. The installation is made in the tank so that the lower segments referred to are positioned where they will be engaged by the pawl during such time as the nozzle member is directing its streams toward the end portions of the tank.

It is a further feature of this invention that hinged ratchet segments are provided above the lower segments so that they can be folded down into position, under which circumstances the unit will have a horizontal movement of uniform angular velocity throughout its entire course of travel.

It is still another object of this invention to provide a device of the class described with means for efficiently and thoroughly cleaning the dome of the tank during the operation of the unit, such means in the preferred form of my invention comprising an auxiliary or dome spray nozzle rotatably supported from the support means in substantially fixed relation therewith.

Means are provided for rotating this dome spray from the secondary feed pipe, and means are also provided for delivering the pressure liquid to the dome spray. In this form of my invention, the pressure liquid is delivered to the dome spray from the secondary feed pipe through a flexible conduit.

It is another feature of this invention that the nozzle unit may be vertically adjusted in the tank, and in order to effect such vertical adjustment without disturbing the position of the dome spray, I employ a telescoping member with positive driving means for moving the dome spray from the secondary feed pipe.

It is a further object of this invention to provide a device of the class described with means for delivering steam into the tank at a point well below the dome.

The details in the construction of a preferred form of my invention together with other objects attending its production will be best understood from the following description of the accompanying drawings which are chosen for illustrative purposes only, and in which—

Fig. 1 is a vertical elevation with parts broken away showing a preferred form of my invention suspended through the dome of a tank car which is shown in section;

Fig. 2 is a fragmentary elevation taken in the direction of the arrow 2 in Fig. 1;

Fig. 3 is a plan section taken in the plane represented by the line 3—3 in Fig. 1;

Fig. 7 is a fragmentary elevation taken in the general direction of the arrow 7 in Fig. 5;

Fig. 8 is a fragmentary enlarged vertical section

taken in the plane represented by the line 8—8 in Fig. 1;

Fig. 9 is a plan section taken along the line 9—9 in Fig. 8; and

Fig. 10 is a fragmentary sectional elevation taken in a plane represented by the line 10—10 in Fig. 8.

More particularly describing the invention as herein illustrated, reference numeral 11 indicates the dome on a tank car or the like which is provided with a flanged manhole opening 12.

Reference numeral 13 indicates a supporting plate of the general character disclosed in the application referred to above, such plate being locked upon the dome member by means of a clamping unit generally indicated at 14.

The plate 13 has a vent opening 15 in which a main feed conduit 16 is supported by means of a clamping collar 17 which in turn is supported from the plate 13 by web members 18.

The top of the main feed conduit 16 is provided with a T connection 19 through which a washing or cleaning liquid is delivered into the main conduit from a suitable source through a delivery connection 20. The lower end portion of the main feed conduit 16 is provided with a bearing flange 21 which is received in a bearing collar 22 on what I may term, a secondary feed conduit 23. The secondary feed conduit is carried by the bearing collar 22 and the flange 21 by a plurality of ball bearings 21' and a threaded ring 22'.

The secondary feed conduit, in addition to the bearing collar 22, comprises a connection section 24 and a nozzle feed and operating casting 25. The lower end portion of the conduit 23 in the nozzle casting 25 is provided with a nozzle feed conduit 26, which I may also term an auxiliary nozzle supporting axle.

The nozzle supporting axle 26 is provided with ports 27 which communicate with a hub member 28 on a nozzle member 29. The nozzle member 29 is shown as comprising a pair of oppositely extending straight nozzles 30 and 30'. The hub member is provided with suitable bearings on the nozzle feed pipe and is retained thereon by means of a bushing 31 and a cap 32. The cap 32 is secured to the nozzle in any suitable manner such as by means of the ears 34, and is keyed or otherwise rigidly secured to a shaft 35 which is supported by a suitable bearing 36 in the end of the nozzle feed pipe and a bearing bushing 37 in the lower portion of the casting 25 opposite the nozzle feed pipe. Through this arrangement the shaft 35 is driven directly from the nozzle unit.

The extending end of the shaft 35 is provided with an eccentric 39 which engages the lower end of what I may term a pitman rod 40. The upper end portion of the pitman rod is attached to a projecting arm or finger 51 formed on a pawl member 52 which is fulcrumed on a pin 53 mounted on the upper end portion of the secondary feed conduit 23.

The pawl member 52 has a vertically extending spring pawl 54 adapted for engagement with a fixed ratchet member mounted on the lower end portion of the main feed conduit and indicated by reference numeral 55. The details in the construction of this fixed ratchet member are best illustrated in Figs. 5 to 7 inclusive where it is shown as comprising a ratchet wheel 57 mounted on the main feed pipe through the medium of a hub 58. The wheel 57 has segments 57a and 57b movable thereon and hinged

so as to fold inwardly to the full line position shown in Fig. 5 where they are out of the path of the pawl member.

Mounted below the space left by these segments, I provide a pair of secondary or auxiliary ratchet segments 59 and 59', such segments being adapted to engage the pawl at an intermediate point on the pawl, and, since the linear travel of the pawl at the point where these segments are engaged is substantially less than its linear travel at the upper end of the pawl where the teeth on the main ratchet wheel 57 are engaged, I may make the teeth on the lower segments 59 and 59' much smaller than the teeth on the upper segments in the ratchet wheel 57. In other words, the segments 59 and 59' are provided with more teeth per unit of length than the main ratchet wheel so that the increments of motion in a horizontal plane during such time as the pawl member is operating on the lower ratchet segment are smaller than the increments of motion when the pawl member engages the upper ratchet segments.

It is through this construction that I obtain the objective, hereinabove referred to, of reducing the angular velocity of the nozzle member in a horizontal plane; also, as pointed out above, the unit is placed in the car so that the pawl engages the lower ratchet segment when the nozzle unit is directed toward the ends of the car. If the device is being used in a tank, the walls of which are spaced equi-distant from the location of the unit, or in a tank which has contained a liquid which is easily removed, the segments 57a and 57b may be folded out into line with the periphery of the ratchet wheel, and under such circumstances the unit will have a uniform angular velocity throughout its entire travel. It will be understood that, under these last named conditions, the pawl member will merely ride over one tooth on the lower ratchet segment for each tooth engaged in the ratchet wheel or in the upper segments 57a and 57b. By way of explanation it might be said that the upper ratchet wheel can be described as having four segments, namely, the two segments 57a and 57b which are hinged on the wheel, and the other two segments which I have indicated by reference numerals 59 and 59' which are fixed portions of the ratchet wheel. Since the nozzle unit is secured to the shaft 35 through the cap 28, it will be seen that the rotation of the nozzle itself about its horizontal axis operates the mechanism described above for rotating the secondary feed pipe and the nozzle unit about a vertical axis.

For the purpose of rotating the nozzle about a horizontal axis in a vertical plane, such rotation being effective to produce the rotation about a vertical axis in a horizontal plane just referred to, I provide a nozzle operating ratchet wheel 65 which is contained within a guard 66 formed in the casting 25 and is keyed to the nozzle hub. This ratchet wheel is engaged by the free end of a pawl 67, the driven end of which is mounted on an eccentric 68 carried by a shaft 69 which in turn extends through a passage 70 provided in the casting 25 where it is supported by bearings 71. A grease cup 72 is provided for the purpose of lubricating and packing the shaft.

The other end of the shaft 69 carries an impeller 73 which is keyed thereto as indicated at 74, and is contained within a guard member or housing 75 formed in the casting 25.

A pressure liquid is delivered from the second-

ary feed conduit 23 through a port 80 formed in the wall of the casting 25 and extending into a box 81. This port in turn communicates through a port 82 with, what I may term, an inlet chamber 83 formed in the box 81.

The inlet chamber 83 contains a pressure regulating valve, generally indicated at 84, and communicates through a port 85 with, what I may term, an outlet chamber 86. The outlet chamber 86 has an outlet port 87 arranged to direct 10 a jet of pressure liquid against the vanes or cups on the impeller wheel 73.

The pressure regulating valve 84, as was hereinabove pointed out, is provided for the purpose of controlling the pressure of the liquid forming 15 the jet, thereby governing the speed at which the impeller is operated. In the usual operation, the cleaning liquid may be delivered to the nozzles under upwardly of eighty pounds of pressure, and I have found that it is desirable to operate 20 the impeller wheel under pressure substantially less than this amount, for example, forty pounds. It will, therefore, be seen that, by providing a pressure regulating valve capable of maintaining a liquid pressure less than the pressure in the 25 conduit, I can maintain a uniform angular velocity in the impeller wheel and the mechanism driven thereby. The pressure-regulating valve in this form of my invention is shown as being of the piston type and comprising a pair of pis- 30 ton members 88 and 89 interconnected by a member 90 and normally positioned on opposite sides of the axis of the ports 85 and 82.

Reference numeral 91 indicates a pressure-controlled piston connected with the piston 89 35 through the bar 92. The inner end portion of the chamber 83 beyond the piston 91 is provided with a port 95 which communicates with the outlet chamber 86 whereby the pressure liquid in the chamber 86 is always reacted upon the pis- 40 ton member 91, the reaction of such pressure being opposed by a compression spring 96 mounted in the opposite end of the chamber 83 against the piston member 88. The compres- 45 sion in this spring may be set to control the pres- 50 sure in the chamber 86 at any desired point by means of a screw 97. An outlet port 97' is pro- 55 vided in the chamber which contains spring 97 to avoid an equalization of pressure around the valve if any liquid leaks past piston 88. It will 60 be seen that this construction provides a balanced pressure regulating valve whereby the pressure in the chamber 86 and the correspond- 65 ing pressure at the outlet port 87 can be positively controlled for any amount less than the pressure 70 of the cleaning liquid which is passing through the feed conduit to the nozzle unit. In other words, the compression spring 96 is adjusted so as to normally hold the piston valve member 84 in the position shown in Fig. 10 so that the pres- 75 sure liquid is free to flow through the ports 80 and 85. The pressure is balanced between piston members 88 and 89 but there is a pressure on the piston 91 which forces the member 84 against the action of the spring 96. This pressure is op- 80 posed by the spring 96 and the passage between the ports will be maintained open until the pres- 85 sure in chamber 83 exceeds the reaction pressure for which the compression spring is set. When the pressure fluid has a pressure in excess of 90 that for which the spring is set, the valve may be closed completely by the pressure in chamber 83 or it may be merely closed to a point at which the pressure in chamber 83 is balanced by the action of the spring. Assuming that the valve 95

Assuming that the valve 75

is closed by the fluid in chamber 83, it will be seen that as soon as the valve closes the pressure in chamber 83 is relieved and the valve is again opened by the spring 96. Pressure fluid admitted to chamber 83 again closes the valve so that under this latter assumption the valve may be described as "fluttering" between an open and closed position. In either event, the resultant effective pressure of the liquid in the jet which 10 impinges upon the vanes in the impeller is uniform and has the value for which the spring 96 is set regardless of the pressure of the wash liquid, provided, of course, the pressure of the wash liquid is greater than that for which the spring 15 is set. By means of this construction, I may operate the impeller wheel at any desired speed obtaining a corresponding speed in the nozzle unit as it rotates in both its vertical and horizontal planes.

20 It is desirable in a device of this character to provide some means for indicating on the exterior of the tank whether or not the device is operating and the approximate speed of operation. Such indication in this form of my invention is 25 obtained by an eccentric or crank section 100 formed on the shaft 35 below the passage through the secondary and main feed conduits. This crank or eccentric member carries a collar 101 which is mounted on the lower end portion of a 30 rod 102. The upper end of the rod 102 extends through a packing 104 in the top of the T member 19 and engages the underside of an indicating lever 105 which is pivoted as indicated at 106 to a short standard 107 formed on the T member 35 or some associated portion thereof. Reference numeral 108 indicates a supporting eye or inverted stirrup positioned over the indicating lever which is provided to facilitate handling the unit. As the nozzle unit and its shaft 35 rotate, 40 the rod 102 is reciprocated effecting a corresponding swinging movement of the lever member 105 such movement being proportioned to the speed of rotation of the nozzle and the shaft 35.

It was also pointed out as one object of this 45 invention to provide a device of the class described with a nozzle type of dome spray unit. In this form of my invention the dome spray unit is generally indicated by reference numeral 110 and is shown as comprising a collar 111 rotatably 50 mounted between fixed collars or flanges 112 and 112' on a sleeve member 113 which is shown as being mounted on the undersurface of a baffle plate 115 supported by the cover mechanism. The collar 111 as illustrated in Fig. 3 is provided 55 with a passage 115 which carries a nozzle 116. Liquid is delivered into the passage 115 from a connection 117 which in turn is connected to a flexible conduit 118 having its inlet in the rotatable secondary feed conduit 24 as indicated 60 at 119.

From the construction so far described, it will be seen that the position of the dome spray nozzle is vertically fixed relative to the cover member, and in order to effect a thorough cleaning 65 of the dome it is desirable to rotate the dome spray nozzle. It is also desirable to provide a device wherein the nozzle unit may be vertically adjusted relative to the cover member. In this 70 form of my invention, the dome spray nozzle is rotated from the secondary feed conduit, and such rotation must, therefore, be effected through means which will permit this vertical adjustment. To effect the rotation of the dome spray nozzle, therefore, I employ a sleeve 121 secured at its upper end to the collar 111 and

slidably receiving another sleeve 122 which is mounted at its lower end upon a plate member 123 which in turn is secured to a guard bar 124. The guard bar 124 is secured at an intermediate point to a guard ring 125 surrounding the ratchet member 55 and is secured at its lower end portion to a bracket 126 which is formed or mounted on the casting 25 so that the plate 123 and the sleeve 122 rotate with the secondary feed pipe 24.

10 For the purpose of driving the sleeve 121 from the sleeve 122 and at the same time permitting vertical movement of the nozzle unit and the sleeve 122, I provide this last mentioned sleeve with an elongated slot 128 which receives a key 15 or pin 129 carried by the outer sleeve 121. In this form of my invention, the key 129 is mounted on a clamping ring 130 and extends through an aperture 131 in the lower end portion of the sleeve 121. From this construction it will be seen 20 that the telescoping sleeves 121 and 122 with their pin and slot connection provide means for positively rotating the dome spray unit from the secondary feed conduit regardless of the vertical position for which the nozzle is adjusted in the 25 tank.

In cleaning a tank or the like, it is desirable 30 to steam the interior of the tank at some time during the cleaning operation. In this form of my invention, this is effected through the medium of a steam inlet conduit 132 which projects upwardly through the cover plate 13 and communicates at its lower end with the interior of the sleeve 113. The steam entering through the conduit 132 passes downwardly through the 35 sleeve 113 into the cooperating sleeve members 121 and 122 finding its outlet through the elongated slot 128 and openings 133 provided in the bottom of the sleeve member 122. The telescoping sleeves 121 and 122 in this form of my 40 invention, therefore, have a dual function.

It is to be understood that, while I have herein 45 described and illustrated one preferred form of my invention, the invention is not to be limited to the precise construction as described above, but 50 includes within its scope whatever changes fairly come within the spirit of the appended claims.

I claim as my invention:

1. A tank cleaning device of the class described 55 embodying: a main feed pipe; means for vertically supporting said main feed pipe; a secondary feed pipe rotatably mounted on the lower end of said main feed pipe; a nozzle feed pipe mounted on said secondary feed pipe at an angle thereto; a nozzle member rotatably 60 mounted on said nozzle feed pipe; a liquid motor supported by said secondary feed pipe and rotatable therewith; means for delivering power liquid to the motor from the secondary feed pipe; ratchet means operated by said liquid motor for 65 rotating said nozzle member in a step by step manner; and means for rotating the secondary feed pipe relative to the main feed pipe by the action of the motor.

2. A tank cleaning device of the class described 65 embodying: a main feed pipe; means for vertically supporting said main feed pipe; a secondary feed pipe rotatably mounted on said main feed pipe; a nozzle feed pipe mounted on said secondary feed pipe in angular relation therewith; a nozzle member rotatably mounted on said nozzle feed pipe; means for rotating said nozzle at a substantially constant speed; means operated by said nozzle member for rotating said secondary feed pipe about its axis relative to 70

- said main feed pipe; and means for increasing and decreasing the angular velocity of said secondary feed pipe during each revolution thereof.
3. A tank cleaning device of the class described embodying: a main feed pipe; means for vertically supporting said main feed pipe; a secondary feed pipe rotatably mounted on said main feed pipe; a nozzle feed pipe mounted on said secondary feed pipe in angular relation therewith; a nozzle member rotatably mounted on said nozzle feed pipe; means for rotating said nozzle; and means for rotating said secondary feed pipe at varying angular velocities about its axis comprising a pawl member fulcrumed on said secondary feed pipe and adapted to move in a substantially vertical plane, means operated by said nozzle for actuating said pawl member, and vertically spaced and angularly offset rack segments non-rotatably mounted on said main feed pipe and adapted to be successively engaged by said pawl member at different points along its length.
4. A tank cleaning device of the class described embodying: a main feed pipe; means for vertically supporting said main feed pipe; a secondary feed pipe rotatably mounted on said main feed pipe; a nozzle feed pipe mounted on said secondary feed pipe in angular relation therewith; a nozzle member rotatably mounted on said nozzle feed pipe; means for rotating said nozzle; and means for rotating said secondary feed pipe at varying angular velocities about its axis comprising a pawl member fulcrumed on said secondary feed pipe and adapted to move in a substantially vertical plane, means operated by said nozzle for actuating said pawl member, and vertically spaced and angularly offset rack segments non-rotatably mounted on said main feed pipe and adapted to be engaged by said pawl member at different points along its length, the rack segments to be engaged by a portion of said pawl nearest to the fulcrum of said pawl having more teeth per unit of length than the rack segments farther from said fulcrum.
5. A tank cleaning device of the class described embodying: a main feed pipe; means for vertically supporting said main feed pipe; a secondary feed pipe rotatably mounted on said main feed pipe in coaxial relation therewith; a nozzle feed pipe mounted on said secondary feed pipe in angular relation therewith; a nozzle member rotatably mounted on said nozzle feed pipe; means for rotating said nozzle member; and means operable by said nozzle member for rotating said secondary feed pipe on said main feed pipe comprising a shaft rigidly connected to said nozzle member, an eccentric on said shaft, a pitman bar mounted at one end on said eccentric, a pawl member fulcrumed on the upper end of said secondary feed pipe for swinging movement in a vertical plane, means connecting the upper end of said pitman bar with said pawl member, a ratchet wheel fixed to said main feed pipe for engagement with the upper portion of said pawl, hinged segments on said ratchet member adapted to be folded inwardly away from the path of said pawl, and fixed ratchet segments mounted below said hinged ratchet segments for engaging an intermediate point on said pawl.
6. For use in combination with a tank having a dome thereon, a cleaning device embodying: a main feed pipe; means for vertically suspending said main feed pipe through said dome; a secondary feed pipe rotatably mounted on the lower end of said main feed pipe in coaxial relation therewith; a nozzle unit mounted on said secondary feed pipe for rotation about an axis substantially normal to said secondary feed pipe; means for rotating said nozzle unit about its axis; means for rotating said secondary feed pipe upon said main feed pipe; a dome spraying nozzle rotatably mounted on said main feed pipe; means for delivering liquid to said dome spraying nozzle; and means actuated by said secondary feed pipe for rotating said dome spraying nozzle about said main feed pipe.
7. For use in combination with a tank having a dome thereon, a cleaning device embodying: a main feed pipe; means for vertically suspending said main feed pipe through said dome; a secondary feed pipe rotatably mounted on the lower end of said main feed pipe in coaxial relation therewith; a nozzle unit mounted on said secondary feed pipe for rotation about an axis substantially normal to said main secondary pipe; means for rotating said nozzle unit about its axis; means for rotating said secondary feed pipe upon said main feed pipe; a dome spraying nozzle rotatably mounted on said main feed pipe; means for delivering liquid to said dome spraying nozzle; and means actuated by said secondary feed pipe for rotating said dome spraying nozzle about said main feed pipe, said last mentioned means including a sleeve secured at its upper end to said dome spraying nozzle, another sleeve secured at its lower end to said secondary feed pipe; and interlocking pin and slot means interposed between said sleeves.
8. For use in combination with a tank having a dome thereon, a cleaning device embodying: a main feed pipe; means for vertically suspending said main feed pipe through said dome; a secondary feed pipe rotatably mounted on the lower end of said main feed pipe in coaxial relation therewith; a nozzle unit mounted on said secondary feed pipe for rotation about an axis substantially normal to said main feed pipe; means for rotating said nozzle unit; means for rotating said secondary feed pipe upon said main feed pipe; a dome spraying nozzle rotatably mounted on said main feed pipe; means for delivering liquid to said dome spraying nozzle; and telescoping means actuated by said secondary feed pipe for rotating said dome spraying nozzle about said main feed pipe.
9. For use in a device of the class described a nozzle unit embodying: a feed conduit; a hollow nozzle axle mounted on said feed conduit in angular relation thereto and communicating therewith; a nozzle member rotatably mounted on said axle, said axle having ports communicating with said nozzle member; a ratchet wheel mounted on said nozzle member; a shaft rotatably mounted on the wall of said feed conduit; a pawl eccentrically mounted on said shaft with its free end engaging said ratchet wheel; an impeller wheel mounted on said shaft externally of said feed conduit; and means for delivering a jet of pressure liquid from said feed conduit against said impeller wheel.
10. For use in a device of the class described a nozzle unit embodying: a feed conduit; a hollow nozzle axle supported by and communicating with said feed conduit; a nozzle member rotatably mounted on said axle, said axle having ports communicating with said nozzle member; a ratchet wheel mounted on said nozzle member; a shaft rotatably mounted in the wall of said feed conduit; a pawl eccentrically mounted on said shaft with its free end engaging said ratchet wheel.

wheel; an impeller wheel mounted on said shaft; and means for delivering a jet of pressure liquid from said feed conduit against said impeller wheel, said last mentioned means comprising an inlet chamber formed in the wall of said feed conduit and communicating through a port with the passage therethrough, a pressure regulating valve in said inlet chamber, an outlet chamber communicating with said inlet chamber and having an outlet port arranged to direct a jet of pressure liquid against the vanes of said impeller.

5 11. A tank cleaning device of the class described embodying: a main feed pipe, means for vertically supporting said main feed pipe; a sec-

ondary feed pipe rotatably mounted on the lower end of said main feed pipe; a nozzle feed pipe mounted on said secondary feed pipe at an angle thereto; a nozzle member rotatably mounted on said nozzle feed pipe; a liquid motor supported by 5 said secondary feed pipe and rotatable therewith; means for delivering power liquid to the motor from the secondary feed pipe; means operated by said liquid motor for rotating said nozzle member; and means operated by the action of the liquid 10 motor for rotating the secondary feed pipe relative to the main feed pipe in timed relation with the rotation of the nozzle.

HAROLD M. RUTH.
